MASKING OR SCREENING DEVICE FOR
LAMPS

Vincent Hartley, Greenfield, England

Application April 18, 1942, Serial No. 439,460
In Great Britain October 6, 1941

8 Claims. (Cl. 240—48.4)

This invention relates to light-screening devices having as their object the controlling of the direction of light rays from a light source such as an electric lamp. The more immediate application of the invention is to the head lamps of motor road vehicles, either as a safety device or mask during light-restriction conditions (e. g. in wartime) or merely as an anti-dazzle device at any time; but the invention is equally applicable to other uses where a non-dazzle beam of light of a controlled cross-section is required, to give adequate vision to persons behind the device whilst the actual light source is largely concealed from the vision of persons in front of the device. Instances, among many, where the invention may find a use other than on road vehicles are, in street lighting, in ship's lighting and in the interior lighting of buildings.

One object of the invention is to provide a device which will allow the maximum emission of light consistent with the nature of control required, which will give a long beam of light, and which may in some of its forms be of simple construction adapted for rapid production by a large proportion of semi-skilled labour. A light-screening device according to this invention, applied to a motor vehicle head lamp, is capable of entirely eliminating dazzle to oncoming persons in normal riding or walking positions, whilst allowing a strong light beam to be projected forwardly and downwardly on to the road for a distance well beyond the minimum required for safe driving.

The invention relates to devices of the known type in which light from an aperture is excluded from a particular zone (for example from above a horizontal plane) by being caused to pass between spaced louvres, plates or baffles (hereinafter referred to generically as louvres) immediately adjacent the aperture, the louvres being so arranged that between any two of them consecutively a plane at the greatest angle without cutting them does not enter the prohibited zone when extended forwardly from the aperture.

According to this invention the improved light-screening device includes an assembly of louvres which is a self-contained unitary structure, capable of being handled as a single composite element without deformation or collapse, and in which the louvres are connected together at three points only, two at the rear and one at the front of the assembly, some at least of the connections being comprised by flanges on the louvres entering and being held by U-sectional gripping and spacing members, and at least one of the con-

nections being provided by the louvres themselves. Usually the louvres will be connected to each other at the rear corners, and at the centre of their front edges. Means will be provided on or in association with the louvres to prevent the light impinging on their upper faces, thus preventing reflection into the prohibited zone. Such an arrangement, whilst preserving all the necessary safety factors by ensuring that no light is directed upwardly, allows of a much wider beam of light than if the front corners were obstructed, and therefore gives better light at the sides of the road where, at times, it is particularly required. This assembly, in use, is secured to a suitable apertured carrier plate, so as to control light passing towards the louvres through the aperture, and is covered or roofed over by a suitable cowl; a diffusing glass is placed behind the assembly of louvres and in front of the light source.

According to another feature of the invention, the several louvres of an assembly are flanged all around (or at least on their front and side edges), the flanges being gapped at each rear corner, and the louvres are connected together at those corners by their flanges entering and being secured to U-sectioned clamping strips passing on to them at the gaps, whilst at the front, the flanges grow into shouldered projections, each of which fits into a slot in the louvre next above it. The front portions of the louvres are also clamped collectively between two members co-operating with a cowl above them, and with the uppermost and lowermost louvre respectively. In addition to being flanged at their edges the louvres will usually have one or more upstanding ribs or ridges extending from side to side and these may comprise pressed-up flanges arranged parallel with each other and with the front edge. Usually all the louvres of an assembly will be of identical form.

The cowl is preferably made separately from side wings enclosing the rear portions of the sides of the louvres, and overhangs those wings, but it may, if desired, be made in one with those wings or the wings may be omitted. The several parts may usefully be secured together by spot welding.

In an embodiment of the invention, already reduced to practice, and adapted for a motor vehicle head lamp, there is a circular apertured back plate flanged peripherally to fit the usual head lamp bezel in place of the glass lens; as assembly of 10 louvres (or thereabouts) flanged upwardly all around and with well-rounded front

corners, the louvres fitting together tongue and groove fashion in spaced relationship at the front centre and being held in U-sectioned clamping and spacing strips at the rear corners, tapered side plates on the back plate, enclosing the louvres at the rear; hooked members on the side plates to engage and hold the louvre assembly by gripping the clamping and spacing strips; a cowl on the back plate to cover over the assembly and side plates; and a diffusing glass held against the back plate behind the louvres, all the parts except the glass being sheet metal stampings and pressings.

In all cases for a road lamp or vehicle lamp the assembly of louvres should be mounted so that the louvres have a slight downward inclination in the direction away from the light source, to ensure that a line joining the upper rear edge of one and the lower front edge of the next one higher will not extend above the horizontal plane in a forward direction.

In its most limited form the invention is characterised according to the example hereinafter described in detail with reference to the drawings.

The invention is illustrated in the accompanying drawings, wherein:

Fig. 1 is a front perspective view of a head lamp mask according to the embodiment above described;

Fig. 2 is a vertical cross-section through the same embodiment;

Fig. 3 is an exploded view (partly-sectional) to illustrate the main elements of the same embodiment, and the manner of their assembly together;

Fig. 4 is an enlarged sectional view of certain parts to show more clearly how the louvres are clamped together at the front; and

Fig. 5 is an illustrative diagram to assist towards a clear understanding of the function of the parts.

Referring to Figs. 1 to 4, there is provided a circular, opaque, back plate 1, flanged around its circumference 2, and suitable for replacing the usual glass front of a headlamp, being dimensioned to replace that front in the usual bezel. The back plate 1 is provided with a rectangular orifice 3 at its centre, and to this back plate, above the orifice 3, is spot welded a roof or cowl 4, of substantially rectangular form in plan, with the front corners rounded, and it is downwardly flanged around its edges, the rear flange 4^a being at a sharp angle and being spot welded to the back plate 1. The cowl is strengthened by a U-shaped rib 4^b and has its rear flange shaped at 4^c for a purpose explained below.

In front of the rectangular opening 3 in the back plate and below the cowl 4 is the improved assembly of louvres. Each louvre 5 consists of a sheet metal pressing of substantially rectangular form, but having the outer front corners rounded to a relatively large radius. The louvres are flanged upwardly at 6 around their edges, the flange being interrupted at the rear of the side edges to form a gap 7, and the louvres each have a series of four parallel upwardly-pressed flanges 8 running from end to end, these flanges being equally spaced across the width of the louvre. Also, at the front of each louvre, there is a semi-circular orifice 9, and adjacent thereto there is a projecting tongue 10, extending upwardly from the flange 6, the upper part of such tongue being of less width than is the lower part.

The louvres 5 are assembled by the smaller

part of the tongue 10 of one being passed into the semi-circular orifice 9 of another, and so on, until the required number (say 10) is obtained, and, whilst these are held in a jig, there is fitted to each rear corner a U-sectioned, gapped clamping member 11, these members being pressed down on to the flanges 6 in a suitably-formed press and then being soldered in position by dipping. The clamps 11 pass on to the louvres 5 from the end, at the gaps 7 formed in the flange 6. An assembly of louvres as formed is a single composite unit, and can be handled without fear of displacement, deformation or collapse.

There is now passed through the several semi-circular openings 9 of the assembled louvres, from below, a stiffening member 12 which is slightly arched transversely and is flanged at its lower end 12^a. The flange 12^a forms an abutment against the lowermost louvre and may be welded thereto.

Spot welded to the underside of the cowl 4, near its front edge, is a V-sectioned depending member 13, whose lower end is upturned to form a hook 14, and the hook enters the opening 9 in the lowermost louvre 5, between the tongue 10 and the strengthening member 12 to support the assembly from the cowl; whilst between the cowl 4 and the uppermost louvre 5 is a flat shouldered positioning member 15 having its upper end bent forward to react against the under face of the cowl, within the V-shaped member 13, and having its lower end reduced to enter the orifice 9 of the uppermost louvre 5, a shoulder 15^a reacting against the top face of the louvre. The combined result is that the several louvres 5 are clamped or vised together between these two members 13 and 15 and are rigidly held. This is more clearly seen in Fig. 4.

Spot welded to the back plate 1, adjacent the sides of the rectangular opening 3 therein, are flanged side pieces or cheeks 16, but these are of a size not to extend so far forwardly as to reach the rounded corners of the louvres, and their forward edge is inclined to agree with the inclined front of the louvre assembly. The side cheeks abut against the shaped parts 4^c of the cowl 4, at the upper rear corners.

Preferably, and as shown, there is attached to the underside of the lowermost louvre 5, a stiffening plate 17, but this will be of shorter length than the louvre so as to leave uncovered openings at the ends of the pressed-up flanges 8, through which openings any rain or other water collected in the louvres may drain. This stiffening member 17 may be a flat plate, as shown, e. g. the piece cut out of the back plate to form the orifice 3, and may be flanged along the rear edge for spot welding to the back plate. (This flange is not shown.)

Secured to the inner face of each side plate 16 is a strip 18 having projecting hooks 19 which, as shown in Fig. 2, encircle the clamping members 11. These strips are so arranged that they hold the assembly of louvres in a downwardly-inclined position relatively to the back plate, as also seen from Fig. 2. It will be seen, therefore, that the composite assembly of louvres is securely held in position at the rear corners (by the hooks 19) and at the centre front (by the members 13 and 15). The rear corners are carried on the side plates 16 which in turn are carried by the back plate, and the centre front is carried by the cowl 4 which also is carried by the back plate. Any other suitable method of mounting the rear portion of the assembly may be adopted,

co-operating either with the side plates 16, or the cowl 4, or directly with the back plate.

A diffusing glass 20 will be positioned behind the opening 3 in the back plate, and this may be supported as shown by means of the strips 21 welded to the rear face of the back plate above and below the orifice, and having their tapered ends bent down behind the glass. Alternatively, the supporting means 21 may be attached at the sides of the rectangular opening 3, instead of at the top and bottom, and could then be spot welded in position on the rear of the back plate at the same time as are the flanged side cheeks 16 secured to the front of the back plate, but in such case it would be necessary to attach to the back plate an additional support for the glass, below the rectangular opening, to prevent its moving downwards between the members 21.

The screen 20 may comprise frosted glass, or, may consist of an acid-etched glass. The frosting or etching will preferably be over the whole surface of the screen, but may, as an alternative, be over some parts only, say for instance in parallel stripes.

During the making-up of the device, the assembly of louvres, and the inner surface of the cowl 1 is sprayed with a suitable pigment to give all the parts a matt surface and so as to be as non-reflective as possible.

Referring now to Fig. 5, the line A—B represents the lower boundary of a prohibited zone into which light from the aperture is not to enter. The louvres 5 are arranged at an angle to the back plate such that the extended plane X—Y which is the plane at the greatest angle between two consecutive louvres without cutting them, will not cut the line A—B. The line O—P represents what would be undesired reflections but which are avoided in this invention. A consideration of Fig. 5 will show further that the upstanding flanges 6 and 8 will obstruct light passing between the louvres and will prevent many rays of light striking the upper surface of the louvres, and thereby will prevent reflection into the prohibited zone. The number of louvres, and their distance apart will vary according to the intensity of light to be emitted and to the purposes for which the light is required. A sheet of clear glass may be secured immediately in front of the louvres to exclude dust, etc.

In modified forms of the invention (not illustrated) adaptable for instance for street lighting, the louvres in each assembly may be of varying size. For example, the uppermost one may be the widest (i. e. may extend furthest from the light), the lowermost one may be the narrowest and those between be varied in progression. Also, instead of the sides 16 being opaque they may be cut away in part, or be transparent, to allow the emission of light sideways from the louvres. With an arrangement of this last-named kind, the louvres, in addition to inclining downwardly in a forwardly direction, may incline downwardly in transverse directions from a central transverse ridge or peak so as to have the same restricted effect transversely as longitudinally.

The whole device will usually be made entirely of metal, either as a built-up assembly of stampings and pressings (as shown), or with parts cast and parts fabricated. Alternatively some of the parts may be of other than metal; for instance the back plate may be of thick, waterproofed card, or of wood.

What I claim is:

1. A light-screening device for a lamp, including an assembly of flat spaced louvres flanged on at least three sides; corresponding gaps in said flanges of said louvres; U-sectioned gripping and spacing members embracing the louvres through said gaps in the said flanges, and securing them together by gripping such flanges; and a shaped tongue and an adjacent slot on the front of each louvre, the tongue of one louvre passing into a slot in the louvre above it to space them at the required distance apart.
- 15 2. A light-screening device comprising an apertured blank, an assembly of flat spaced louvres in front of the aperture, the louvres being flanged on at least three sides; corresponding gaps in said flanges of said louvres; U-sectioned gripping and spacing members embracing the louvres through the said gaps in the said flanges, and securing them together by gripping such flanges; a shaped tongue and an adjacent slot on each louvre, the tongue of one louvre passing into a slot in the louvre above it to space them at the required distance apart; a cowl secured to the apertured blank above the louvre assembly, side cheeks on the blank, below the cowl, to cover over a portion of the assembly, and hook members on said side cheeks to engage the U-sectioned gripping and spacing members and hold the assembly in position.
- 25 3. A light-screening device comprising an apertured blank, a cowl secured to the blank above the aperture, an assembly of flat spaced louvres below the cowl and in front of the aperture, the louvres being flanged on at least three sides; corresponding gaps in said flanges of said louvres; U-sectioned gripping and spacing members embracing the louvres through said gaps in the said flanges, and securing them together by gripping such flanges; a shaped tongue and an adjacent slot on each louvre, the tongue of one louvre passing into a slot in the louvre above it to space them at the required distance apart; a thrust member positioned between the cowl and the uppermost louvre of the assembly, and a tension member positioned between the cowl and the lowermost louvre of the assembly.
- 35 4. For use in the head-lamp of a motor vehicle, a light-screening device comprising a circular apertured back plate flanged peripherally to fit the usual head lamp bezel in place of the glass lens; an assembly of louvres flanged upwardly all around, the front corners of said louvres being flanged, the louvres having tongues and grooves interlinked to hold the louvres in fixed and spaced relationship at the front centre; U-sectioned clamping and spacing strips at the rear corners of said assembly; a plurality of upwardly-pressed flanges formed on the louvres and adapted to prevent light falling on the top faces thereof; tapered side plates on the back plate, at least partly enclosing the louvres at the sides; hooked members in the side plates gripping the clamping and spacing grips to engage and hold the louvre assembly; a cowl on the back plate to cover over the assembly and side plates; and a diffusing glass held against the back plate behind the louvres.
- 45 5. A light-screening device including a unitary assembly of louvres of identical form, each louvre being flanged upwardly all around except for a gap at each rear corner, and each having an upstanding shouldered tongue and an adjacent slot on the front edge, the tongue of one louvre entering the slot in the one above it to maintain the correct spacing at the front, a U-sectioned
- 55
- 60
- 65
- 70
- 75

clamp connecting said louvres together at each rear corner, one jaw of each said clamp being slotted and embracing the louvres at the said gaps so that the adjacent flanges enter between the jaws the louvres being gripped therein at the required spacing, and each louvre having upwardly casting flanges extending transversely across it to prevent light impinging on and being reflected from its upper face.

6. A light-screen device according to claim 5, and having an apertured blank with its aperture immediately behind the louvre assembly, a cowl projecting forwardly from the blank just above the louvre assembly, side plates extending forwardly from the blank immediately at the sides of the louvre assembly, means on the side plates to engage and hold the U-section clamps of the assembly and means on the cowl to engage and hold the uppermost and lowermost louvres of the assembly at the front.

7. A light-screening device comprising an assembly of spaced flat louvres of identical form each upwardly flanged except for a gap at each rear corner, the flange of each at the centre front extending upwardly first in a wider and then in

a narrower portion and each louvre having a slot immediately behind such upwardly-extending portion, the louvres being arranged with the narrower of the upwardly-extending portions entering the slot of the next higher louvre, a stiffening member passing through the slots of all the louvres, means connecting the louvres together on their rear corners, a cowl lying over the assembly, a hook member secured to the underface of the cowl and hooking into the slot of the lowermost louvre and a thrust member secured to the underface of the cowl and entering the slot of the uppermost louvre, each louvre having a number of pressed-up lips extending transversely to prevent light falling on their upper faces.

8. A light-screening device according to claim 7 and including an apertured blank shaped to fit the bezel of a motor car head-lamp in place of the usual glass, the aperture being arranged behind the louvre assembly, side plates extending forwardly from such blank, and hook means thereon to engage and hold the means connecting the louvres together on their rear corners.

VINCENT HARTLEY.
